UNITED STATES PATENT OFFICE.

WILLIAM C. SHANNON AND LEONARD D. MULLEN, OF SELMA, ALABAMA.

AUTOMATIC AIR-BRAKE.

SPECIFICATION forming part of Letters Patent No. 735,603, dated August 4, 1903.

Application filed December 30, 1902. Serial No. 137,200. (No model.)

To all whom it may concern:

Be it known that we, WILLIAM C. SHANNON and LEONARD D. MULLEN, citizens of the United States, residing at Selma, in the county 5 of Dallas and State of Alabama, have invented a new and useful Automatic Air-Brake, of which the following is a specification.

This invention is an air-brake particularly adapted for use upon electrical railway-cars; 10 but it will of course be understood that the brake can be applied to any and all constructions of cars.

The object of the invention is to provide an air-brake mechanism in which the air for 15 applying the brake will be condensed by means of a mechanism connected with the axle of the car to which the brakes are applied, and another object of the invention is to provide for automatically cutting off the pumping 20 mechanism the moment a predetermined pressure is attained in the condenser-cylinder, and a still further object is to provide for applying the brakes gradually or suddenly, as the occasion may require. 25 With these various objects in view and certain others, as will hereinafter appear, the invention consists in the novel features of construction, combination, and arrangement, all of which will be fully described hereinaf- 30 ter and pointed out in the claims.

In the drawings forming a part of this specification, Figure 1 is a view in elevation illustrating the practical application of our invention to the bottom of the car. Fig. 2 is 35 a perspective view of the pumping mechanism. Fig. 3 is a top plan view of the pumping mechanism, the governor being shown in section. Fig. 4 is a view taken on the line 44 of Fig. 3 looking in the direction of the 40 arrow. Fig. 5 is a detail perspective view of the cross-head connected to the piston-rod. Fig. 5^a is a detail perspective view of the link. Fig. 5^b is a detail perspective view of the block carried by the cross-head and adapted 45 to slide in the link. Fig. 5^c is a detail perspective view of a crank-arm for raising and lowering the link. Fig. 6 is a view showing the reservoir and the portion of the governor-cylinder arranged adjacent thereto. Fig. 7 50 is a detail sectional view of the pumping or condenser cylinder. Fig. 8 is a detail sectional view of the brake-cylinder, the brake-

lever being shown in top plan. Fig. 9 is a detail perspective view showing the guide for the piston-rod of the brake-cylinder. Fig. 10 55 is a detail perspective view of the controller. Fig. 11 is a sectional view of the same. Fig. 12 is a side elevation showing the exhaust-outlet. Fig. 13 is a detail perspective view of the valve. Fig. 14 is an inverted perspective showing the inner end of the hand-lever. 60

In carrying out our invention we employ a drop-frame A, which is bolted to the bottom of the car adjacent to the end of the said car. It will be understood that the brake mechanism is arranged at each end of the car; but we have only shown one mechanism, as that will be sufficient to fully illustrate our invention, inasmuch as mechanisms at each end are identical. One member of this drop-frame 70 is enlarged, as shown at A', said enlargement being essentially in the form of a circle, and secured to said enlarged portion is the cylinder B, having a head B' secured thereto by means of bolts B², which pass through the 75 said head and also through the circular plate A'. The plate A' and the head B' may be constructed with threaded annular flanges A² and B³, respectively, which are adapted to engage the internally-threaded ends of the cylinder B. 80

A piston C works in the cylinder B and has a piston-rod D connected thereto, which works through the stuffing-box D', arranged upon the circular plate A', the end of said piston-rod passing through the opposing member of the drop-frame and through a stuffing-box 85 D', carried by the said member, as most clearly shown in Fig. 2. The cylinder A is provided with inlet-valves E, through which 90 air is driven into the cylinder, and the outlet-valves F, through which air is forced from the cylinder into the branch pipes F', which communicate with the pipe F², which leads to the reservoir G, and by the reciprocation 95 of the piston air is driven into the cylinder B and forced into the reservoir G. In order to thus pump or compress the air within the reservoir, we arrange an eccentric H upon the adjacent axle of the car, said eccentric being 100 sectional, so that it can be secured to the axle without removing the same, and surrounding this eccentric H is a sectional strap H', to which is connected the pitman-rod H²,

said pitman-rod being pivotally connected to a link I, adjacent to the upper end thereof, said link having a block K sliding therein, which block is carried by a stud K', projecting laterally from the cross-head L, said cross-head being secured to the piston-rod D by means of a set-screw L'. This cross-head has a depending arm L², which is enlarged at its lower end and provided with a horizontal bore L³, through which passes the guide-rod L⁴ for the purpose of guiding the cross-head, said guide-rod being held stationary between the upright members of the drop-frames, as most clearly shown in Figs. 1 and 2. The lower end of the link I is pivotally connected to a crank-arm M, which is carried by a block M', movable in a vertically-slotted guiding-frame M², suspended from the drop-frame by means of a bracket M³.

It is obvious that by raising and lowering the link I the throw of the piston is regulated, and when the said link is moved to a certain position the operation of the piston will cease altogether, thereby checking the pumping and condensing operations. This principle is utilized for the purpose of stopping the pump as soon as the predetermined pressure has been obtained in the reservoir, and in order to automatically cut off the pump as soon as such pressure has been obtained we provide a governor, which embodies in its construction a cylinder N, connected with the reservoir by means of a pipe N', and in this cylinder is arranged a piston O, having a piston-rod O' connected thereto and extending through an adjustable nut O², carried by a suitable bracket O³, and surrounding the piston-rod, between the piston-head and the adjustable nut O² is a coiled spring O⁴, and by adjusting the nut the tension of the spring can be regulated, so that any desired pressure can be obtained within the reservoir before the piston becomes operative. The free end of the piston-rod O' works through a bracket O⁵, attached to the cylinder-head B', as most clearly shown in Fig. 2. This piston-rod O' is connected to the upper end of the lever P, which lever is mounted upon the end of the rock-shaft P', journaled in a suitable bearing P², connected to the drop-frame A, the opposite end of said rock-shaft P' having an arm P³, which is connected also to the crank-arm M, so that when the pressure in the reservoir is sufficient to force the piston forwardly the lever P is moved forward, rocking the shaft P', which elevates the arm P³, causing the link I to be lifted, and as this movement continues the stroke of the piston C will become less and less until the link reaches a position where it will rock freely upon the stud K' without communicating any motion to the cross-head L. Thus it will be seen that the pump can be cut off automatically as soon as a predetermined pressure has been obtained in the reservoir, and this predetermined pressure is regulated by means of an adjustable nut O².

In order to apply the air so condensed, we employ a controller of peculiar mechanism and which is preferably arranged at a point 70 within easy reach of the motorman, as most clearly shown in Fig. 1. The detail construction of our controller is clearly illustrated in Figs. 10, 11, and 12, and by reference thereto it will be noted that the casing 75 is composed of two sections Q and Q', bolted together, as shown at Q², the section Q being connected to the brake-cylinder by means of a pipe connection Q³, while the section Q' is connected to the reservoir by means of a pipe 80 connection Q⁴. The upper section is conical in form and has a conical-shaped valve R arranged therein, said valve being hollow and having an upper stem R', which projects upwardly through the casing, and also 85 with a lower stem R², which projects down into a recess Q⁵ and rests upon the spring R³, constructed in said recess and surrounding the stem R². The upper stem R' has a squared portion R⁴, upon which fits the handle S, said handle having ribs S' upon the lower faces adapted to engage notches S², formed upon the upper end of casing Q. The coiled spring S³ surrounds the upwardly-extending portion of the stem R' 95 and is held in place by means of a nut S⁴ for the purpose of holding the handle in its adjusted position. The valve R is hollow and is provided with an opening T, preferably circular in form and which is adapted 100 to be brought into engagement with the pipe connection Q³, which communicates with the brake-cylinder, said opening T being of such size that when brought into communication with the brake-cylinder the brake will be 105 gradually applied, the air entering the brake-cylinder U through the pipe U', which connects with the pipe connection Q³, said brake-cylinder having a piston U² arranged therein, to which the piston-rod U³ is attached, 110 said rod being connected to the brake-rod U⁴, and this piston-rod works through a guide V, carried by the rods V', which project from the hanger V², arranged to support the brake-cylinder U. The valve also has a larger opening T', which can be brought into engagement 115 with the pipe connection Q³ for the purpose of releasing the air instantly and applying the full force thereof to the brake-cylinder, so that the brakes can be immediately or suddenly applied. The valve is also provided with a groove or recess T² upon the exterior thereof and which is adapted to be brought 120 into engagement with the exhaust-opening T³, produced in the casing Q, so that after 125 the brakes have been applied and the valve turned so as to cut off communication between the reservoir and brake-cylinder the air in the brake-cylinder may exhaust for the purpose of releasing the brakes. The handle S is provided with the ribs or lugs S', which engage the notches, so that by turning to one notch the operator will know that the 130 brakes will be gradually applied and by

turning to another notch the brakes will be suddenly applied and that in order to cut off communication and permit exhaust the valve should be moved until the ribs or lugs engage the third notch. If desired, the air-pressure gage can be arranged in connection with the controller, a suitable nipple W being provided for this attachment.

It will thus be seen that we provide an exceedingly-simple and highly-efficient construction of air-brake particularly adapted for use in connection with railway-cars, one which will automatically store the air required while the car is in motion and one which will automatically check the pumping operation as soon as a predetermined pressure has been obtained.

Having thus fully described our invention, what we claim, and desire to secure by Letters

20 Patent of the United States, is—

1. The combination with a pump, of a piston therein, a cross-head connected to the piston, means connected to the axle adapted to operate the pump, a reservoir connected to the pump, a brake-cylinder having connection with the reservoir, a governor-cylinder connected with the reservoir, an adjustable governor, a link pivotally connected to the pump-operating cylinder, a block connected 25 to the cross-head and adapted to slide in said link, and means connecting the governor and the lower end of the link.

2. The combination with a drop-frame, of a cylinder connected thereto and having a piston-rod therein, the piston-rod connected to the piston and working through the members of the drop-frame, a cross-head connected to the piston-rod, the drop-frame carrying means for guiding the said cross-head, an eccentric arranged upon the axle, a strap surrounding said eccentric, and a pitman connected thereto, a link pivotally connected to the pitman, a block adapted to slide in said link, said block being carried by the cross-head, an adjustable governor and means connecting the governor and lower end of the link whereby the said link can be adjusted for the purpose of regulating the stroke of the piston of the pump, as specified.

3. In an air-brake mechanism, the combination with a governor-cylinder connected to the reservoir by means of a pipe, a piston in said governor-cylinder, a piston-rod connected thereto, a guide connected also to the governor-cylinder, an adjustable nut arranged in said guide, the piston-rod projecting through said adjustable nut, and a coiled spring surrounding the piston-rod one end bearing down on the piston, the opposite end 55 bearing upon the adjustable nut, substantially as specified.

4. The combination of a drop-frame, of a cylinder connected thereto, a piston arranged in the cylinder, a piston-rod connected to the 65 piston and working through the vertical

members of the drop-frame, a cross-head carried by the piston-rod, said cross-head being guided by means of the guide-rod carried by the drop-frame, the eccentric, strap and pitman, the link connected to the pitman, the block arranged in the link and connected to the cross-head, a rock-shaft journaled to the drop-frame, a rocker-arm connected to one end of said shaft, said rocker-arm being connected with the lower end of the link, a lever 75 connected to the opposite end of the rock-shaft, the piston-rod to which the upper end of the lever is pivotally connected, the piston to which the said piston-rod is attached, said piston being arranged in the governor-cylinder and provided with means for regulating the operation thereof, a pipe connected to the governor-cylinder, a reservoir, said reservoir being connected with the governor-cylinder and also with the pump-cylinder, a 80 brake-cylinder connected also with the reservoir, a piston arranged in the brake-cylinder and having its rod connected with the brake mechanism and means for controlling the air in the reservoir, as specified. 90

5. In an air-brake mechanism and controller comprising a casing formed in two sections, one section being connected with the reservoir and the other section with the brake-cylinder, a valve arranged in the casing and 95 provided with an opening adapted to gradually apply the brake and also an opening adapted to forcibly apply the brake and an exhaust-opening to permit the escape of air from the brake-cylinder after the brakes 100 have been released, as specified.

6. In an air-brake mechanism and controller comprising a casing formed in two sections, one section being connected with the reservoir and the other section with the brake-cylinder, a hollow conical valve having an upwardly-projecting stem and also a downwardly-extending stem, said downwardly-extending stem resting in the recess produced in the lower section of the casing, 110 a coiled spring arranged within the recess and upon which the downwardly-extending stem rests, the upwardly-extending stem having a squared portion, a hand-lever fitted upon said squared portion, said hand-lever 115 having ribs or lugs upon its under side adapted to engage notches produced in the upper end of the casing, a spring arranged upon the upper end of the stem and adapted to bear upon the hand-lever, said valve having 120 two openings of different sizes and a groove or recess upon the exterior, the casing having an opening adapted to permit the exhaust of air, as specified.
